(57) **CLAIM**

The ornamental design for supersonic aircraft with in-flight refueling system, as shown and described.

DESCRIPTION

FIG. 1 is a top, front and left side perspective view of supersonic aircraft with in-flight refueling system, embodying our new design;

FIG. 2 is a left side elevational view thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a top, front and left side perspective view thereof with the wings shown in a folded position.
